UNITED STATES PATENT OFFICE.

CHARLES S. ROGERS, OF HOT SPRINGS, ARKANSAS, ASSIGNOR TO ALBERT C. DEAVER AND HAMP WILLIAMS, BOTH OF HOT SPRINGS, ARKANSAS.

EYE-SCREEN FOR HORSES.

No. 903,108.

Specification of Letters Patent.

Patented Nov. 3, 1908.

Application filed September 23, 1907. Serial No. 394,242.

To all whom it may concern:

Be it known that I, CHARLES S. ROGERS, a citizen of the United States, and resident of Hot Springs, Garland county, Arkansas, have invented certain new and useful Improvements in Eye-Screens for Horses, of which the following is a specification containing a full, clear, and exact description, reference being had to the accompanying drawings, forming a part hereof.

My invention relates to an eye-screen for horses, and consists in certain novel features of construction and arrangement of parts, which will be hereinafter more fully set forth, pointed out in the claims, and illustrated in the accompanying drawings, in which:—

Figure 1 is a perspective view of the screen as applied for use; Fig. 2 is a view of the complete apparatus when not in use; Fig. 3 is an elevation of one of the eye-screens; Fig. 4 is a vertical section taken through the center of one of the eye-screens.

Referring by numerals to the accompanying drawings:—1 indicates the eye-screen, which may be constructed of different materials, such as common wire screening, brass, copper, or cloth net, and various other materials of various sized mesh. The screening 1 is mounted on a wire frame, and said frame is composed of a marginal wire 2, which is shaped so as to conform with the contour of the animal's head surrounding the eye, and is provided with an arched portion 3, which, when the device is in use, occupies a position above the animal's eye.

Secured to the marginal wire 2 are cross-wires 4, the ends of which are connected to the marginal wire 2 in any suitable manner, and the intermediate portions of the wires 4 are connected to one another in any other suitable manner. The wires 4 are so bent as to form an arch-shaped frame for the screening; and, when the device is applied to the animal, said frame is located a sufficient distance from the eye so as not to affect the vision or the movement of the eye-lids. The wire screening 1 is located on top of said arch-shaped frame, composed of the wires 4, and is secured thereto by outside wires 4^a, which lie immediately over the wires 4 and being secured thereto in any suitable manner.

Located on the marginal wire 2 is a band of tape 5, which surrounds the wire 2 and the lower edge of the netting 1, and which

tape is secured to the netting or the wire, or both, by any suitable means. Located on the inside of the band 5 is a piece of flexible material 5^a, adapted to fit snugly around the animal's eye, so as to prevent flies, mosquitos, and other insects, from crawling in between the animal's head and the screen and having access to the eye. In place of this tape, leather, metal, or any other material suitable for this purpose may be used.

The screens are of like construction, one for each eye, and are secured together by an adjustable strap 6, which, when the screen is in use, passes across the forehead of the animal. The ends of the strap 6 are secured to the lower portions of the screens. The top portions of the screens are held in proper relative positions by means of straps 7, which, when the screens are in use, lie across one another on the forehead of the animal.

9 indicates an adjustable strap which is adapted to pass around the animal's neck, and to which the upper ends of the straps 80 7 are secured.

10 indicates a brow-band, the ends of which are secured to the strap 9, the straps 7 being located beneath the brow-band 10 when the screen is in use.

11 indicates buckles fixed to the strap 9, and to which are attached the upper ends of straps 12, fixed at their lower ends to the eye-screen frames.

Secured to the eye-screens are straps 13, 90 and secured to said straps 13 are pieces of elastic 14, and to said pieces of elastic 14 are secured straps 15, one of which is provided with a buckle 16.

When the ends of the straps 15 are buckled together, the elastic pieces 14 permit the free movement of the animal's jaws, preventing any chafing and relieving any unnecessary strain.

The screens are of peculiar shape, the 100 marginal wires 2 being provided with the arched portions 3; said arched portions, when the screens are in use, lying above and fitting over that portion of the animal's head immediately above the eyes. It will be 105 seen from the drawings that the arched portion projects almost at right angles to the marginal wire, so as to present, in plan view, practically a straight line.

The device is adjustable by means of the 110

various straps so as to fit any sized head; and, when applied, thoroughly protects the eyes of the animal from insects, dust, and the like.

5 When it is desired to apply the screen to the animal's head, the adjustable strap 9 is buckled around the throat of the animal, the brow-band 10 passing across the forehead, and by means of the adjustable straps 7, 12, 10 6, and 15, the screens are properly positioned over the eyes of the animal.

As heretofore stated, the screens may be made of any suitable material, likewise the framework of the screens and the marginal 15 edge of the same may be bound with any suitable material, preferably a soft or yielding binding, so as to produce a snug fit. The screen as hereinbefore described is cheap in construction and adjustable to fit various 20 sized heads, is easily applied and removed, and makes an effective protection for the eyes of the animal; and may be used with a bridled or unbridled animal.

I claim:—

25 1. The herein described eye-screen for animals, comprising a pair of frames, the edges of which are arched at the top, screen sections located on said frames, adjustable straps for maintaining the frames in position on an animal's head, and an adjustable strap uniting the frames.

30 2. The herein described eye-screen for animals, comprising a pair of frames, said frames consisting of a marginal wire provided with an arched portion, arch-shaped cross wires secured to said marginal wire, screening fixed on said arch-shaped cross wires and marginal wires, binding straps secured to said marginal wires, and adjustable 40 means for securing said frames to the animal's head.

3. The herein described eye-screen for animals, comprising skeleton frame works adapted to fit that portion of the animal's 45 head surrounding the eyes, screening mounted on said frame works, an adjustable strap for securing said frame works together,

elastic straps adapted to pass beneath the jaw of the animal, adjustable straps adapted to pass over the forehead of the animal, and 50 an adjustable strap adapted to pass around the neck of the animal, to which said adjustable straps may be secured.

4. The herein described eye-screen for animals, comprising a skeleton frame, a marginal wire provided with an arch-shaped portion, wire screening secured to said skeleton frame and marginal wire, and an adjustable strap for supporting said frame in the proper position on the animal's head. 60

5. The herein described eye-screen for animals, comprising frames constructed to fit around and over the animal's eyes, the tops of which frames are arched; sections of wire screen fitted onto said frames, a section of 65 flexible material secured to the edges of the frames; and means whereby the frames are held in proper position on the animal's head while in use.

6. An eye-protector for animals, constructed of sections of reticulated material adapted to fit over and around the eyes of the animals, the tops of which sections are arched; and means whereby said sections of 75 reticulated material are held in position on the animal's head while in use.

7. An eye-protector for animals, comprising a pair of sections of reticulated material adapted to fit over and around the eyes of the animals, the tops of which sections are 80 arched; means whereby said sections of reticulated material are held in position on the animal's head while in use, and a binding of flexible material fixed to and extending entirely around the marginal edges of 85 the sections.

In testimony whereof, I have signed my name to this specification, in presence of two subscribing witnesses.

CHARLES S. ROGERS.
